UNITED STATES PATENT OFFICE.

SOLOMON LEVIN, OF HOLDREGE, NEBRASKA.

SHOULDER-PAD.

1,151,696.

Specification of Letters Patent. Patented Aug. 31, 1915.

Application filed June 9, 1914. Serial No. 844,022.

To all whom it may concern:

Be it known that I, SOLOMON LEVIN, a citizen of the United States, residing at Holdrege, in the county of Phelps and State 5 of Nebraska, have invented certain new and useful Improvements in Shoulder-Pads, of which the following is a specification.

My invention relates to new and useful improvements in coats particularly those 10 worn by mail carriers and other persons that are employed in carrying bags wherein the straps are brought over the shoulders, and has for its primary object to provide a shoulder pad that carries a hook and is designed 15 to fit snugly upon the shoulder of a coat in such manner that the strap of a bag or satchel may be mounted within the hook and across the pad and wear on the material of which the coat is formed is prevented. 20

Another object of importance is to provide a pad that is approximately concavo-convex, will partially relieve the strain on the shoulder of a person carrying a bag or 25 satchel with a strap thereon and also eliminate wear on the goods.

Another object is to provide a pad of the character described that may be worn in such manner that it will not be readily detected and a neat appearance presented also 30 proving comfortable to the wearer.

Another object is to provide a pad of the character described that is of a simple construction, capable of being readily attached 35 and detached so that it may be carried in a pocket of the wearer's coat when not in use and inexpensive to manufacture.

The above and additional objects are accomplished by such means as are illustrated 40 in the accompanying drawings, described in the following specification and then more particularly pointed out as claimed.

With reference to the drawings, wherein I have illustrated the preferred embodiment 45 of my invention as it is reduced to practice and throughout the several views of which similar reference numerals designate corresponding parts, Figure 1 is a perspective view showing my improved pad in use, Fig. 50 2 is a transverse sectional view taken through the pad and hook, and Fig. 3 is a fragmentary plan view showing the manner of securing the pad to the shoulder and lapel portion of a coat.

55 Referring to the drawings by characters

of reference the numeral 1 designates as an entirety the body portion of my improved pad which consists of a sheet metal plate that is approximately triangular in shape and is concavo-convex. A strip or layer of 60 felt or some other suitably soft material 2 is stitched about the periphery of the metallic body 1 and is to be worn adjacent to the material of the shoulder of the coat. A fabric layer or strip 3 is stitched about the top 65 of the body 1 and said strip is of the same material preferably of which the suit or coat is formed. Hinged at one end to the apex end of the pad is a strap supporting hook 4 that consists of a metallic body 5 and fabric strips 6 on either side. The hook 5 is formed in the same manner as is the pad. 70

The body of the hook is designed to lie flat upon the upper face of the pad in such manner that the hook is disposed in approximately the central part of the pad and the weight evenly distributed. A pin fastening element designated 7 as an entirety is inserted through the metallic eyelets 8 in the hook and secured to the material of the 80 coat designated 9 as an entirety underneath the collar 10 thereof. The hook 4 may be stitched if desired to the apex end of the pad to provide a secure fastening therefor. 75

It will be readily seen that my improved pad may be easily attached or worn upon the shoulder of a coat in such manner that the strap of a bag or satchel may be carried thereupon and is prevented slipping. The pad in being curved in cross section or concavo-convex closely fits about the shoulder and prevents wear thereon. The weight of the satchel or bag being carried is evenly distributed and blisters or sore shoulders which often occur from carrying bags or 90 satchels of the character described, are obviated. 95

By virtue of having the strap-supporting hook hingedly connected to the shoulder-engaging member, the mail carrier can bend his body without danger of the mail bag strap slipping from the pad, for when the carrier's body is assuming a bended position, the hook will be swung outwardly and effectively support the bag therefrom. Another advantage derived from hingedly connecting the hook, is that when the carrier is about to pass over his shoulder the strap of a mail bag filled with mail, the carrier can 100 bend his body sidewise in the direction of 105 110

the mail bag, and thereby swing the hook outwardly and admitting of the expeditious engagement of the mail bag strap over the bill of the hook, so as to admit of the lifting 5 of the bag when a carrier's body is assuming an upright position.

In practice, I have found that the form of my invention, illustrated in the drawings and referred to in the above description, as 10 the preferred embodiment, is the most efficient and practical; yet realizing that the conditions concurrent with the adoption of my device will necessarily vary, I desire to emphasize the fact that various minor 15 changes in details of construction, proportion and arrangement of parts may be resorted to, when required, without sacrificing any of the advantages of my invention, as set forth.

Copies of this patent may be obtained for five cents each, by addressing the "Commissioner of Patents, Washington, D. C."

What is claimed is:—

A shoulder pad including a shoulder-engaging member, substantially triangular in configuration, and curved in cross section, a hook located on the upper surface of the shoulder-engaging member and having the 25 terminal of its shank hingedly secured on the apex of the shoulder-engaging member, fastening means for securing the shoulder-engaging member to the garment, and located at the apex of the said shoulder-engaging member.

In testimony whereof I affix my signature in presence of two witnesses.

SOLOMON LEVIN.
